Primary Examiner — Susan Moon Lee(74) *Attorney, Agent, or Firm* — NSIP Law(57) **CLAIM**

We claim the ornamental design for a digital clipboard reader, as shown and described.

DESCRIPTION

FIG. 1 is a front perspective view of a digital clipboard reader showing our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is a rear perspective view thereof;

FIG. 9 is a second front perspective view of the digital clipboard reader of FIG. 1 shown in an open configuration;

FIG. 10 is a second view of the digital clipboard of FIG. 9, showing an example environment; and,

FIG. 11 is a partial enlarged view of FIG. 1 that is included to more clearly depict the design from the front perspective view (a-a', b-b', c-c', d-d') of FIG. 1.

Features shown in broken lines in FIG. 10 form no part of the claimed design.
